UNITED STATES PATENT OFFICE.

JOHN B. OWENS, OF METUCHEN, NEW JERSEY.

METHOD OF AND MEANS FOR BALANCING DRAFT IN TUNNEL-KILNS.

1,278,991.

Specification of Letters Patent. Patented Sept. 17, 1918.

Original application filed March 3, 1917, Serial No. 152,444. Divided and this application filed November 16, 1917. Serial No. 202,330.

To all whom it may concern:

Be it known that I, JOHN B. OWENS, a citizen of the United States, residing at Metuchen, county of Middlesex, and State of New Jersey, have invented certain new and useful Improvements in Methods of and Means for Balancing Draft in Tunnel-Kilns, of which the following is a specification.

This invention relates to tunnel kilns and has for its object the provision of a method of and means for providing a balanced draft therefor.

In tunnel kilns it has been customary to provide a sand seal to shut off the heat in the tunnel so that it will not have access to the under parts of the appliances, for instance, cars, which carry the ware being burnt. Such cars are usually provided with a protecting platform of refractory material. The integrity of said seals is difficult to maintain.

The present invention has for its object the provision of a method and means by which a sufficiently low temperature may be maintained below the platforms of the cars to prevent injury to the trucks and other mechanical parts, whereas the space above the car platforms will be maintained at the temperature required for burning the ware.

This eliminates the necessity of a sand seal and simplifies both the construction and operation of the kiln. To accomplish this object I provide a method and means by which semi-inert air is maintained below the car platforms as an insulator from the heat above said platforms and supplements the insulating action of the protective platforms. The inertness of the air in the space below the platforms is occasioned by sealing that space from the outside air and preventing it from having direct connection with the draft outlet to the stack except by air leakage through the space between the tunnel walls and the edges of the refractory car platforms and the spaces between the cars. When it is desired to take advantage of the air leakage referred to and to circulate enough air under the car platforms to cool the working parts of the cars, communication between the space below the car platforms and the outside air is established by operating dampers controlling inlet openings whose number may vary according to requirements. The air leakage in question, while not interfering with conditions to be maintained above the

car platforms, will have sufficient cooling effect to prevent the accumulation of injurious heat below the car platforms.

When I refer to car platforms, I have reference to any conveyer support or platform on which the ware is carried: cars are commonly employed for that purpose, but other conveying means could be used.

The embodiment of the invention shown in the drawings and hereinafter described is to be considered as illustrative, rather than restrictive, of the scope of the invention, as other forms may be resorted to without changing the essential principles thereof in carrying out my new method.

The present application is a division of my application Serial No. 152,444, filed March 3, 1917, for balanced and controllable draft for tunnel kilns.

In the accompanying drawings:

Figure 1 is a half plan, half sectional view, of the kiln of my application, Serial No. 152,444 provided with my present invention, certain parts being broken away, and others shown in dotted lines;

Fig. 2, a side elevation with certain parts in section;

Fig. 3, an enlarged detail section on line 3—3, Fig. 1; and

Fig. 4, a like view on line 4—4, Fig. 1.

The kiln has an air-lock 1 whose doors are shown at 2 and 3. After the ware has passed from the lock 1 and under the door 3, it is in the kiln proper 4 and is heated until it reaches a point opposite the furnaces 5. The ware is cooled as it passes beyond the furnaces 5 into the cooling zone 6, thence into the air-lock 7 having doors 8 and 9 and finally out of the end of the kiln, the direction of travel being shown by the arrow in Fig. 1.

The stack 10 may be located immediately adjacent the kiln or at a point removed therefrom. When referring to the "stack" in the following description and claims, I am to be understood as including any means for inducing draft and that term may comprehend a plain stack, a fan, or a combined fan and stack, or, any means for inducing draft. Referring first to Figs. 1, 2, and 4, the stack communicates with the kiln proper 4 by a flue or duct 11, and down flues 12 and 13 which are joined to the kiln by ports or openings 14. Dampers 15 of the slide, butterfly, or any other type, control commun-

cation between the ports 14 and the main flue 11. The regulation of these dampers enables the main draft from the kiln through the ports 14 to be changed, as desired, irrespective of the controls now to be described.

Extending alongside the kiln on its opposite sides are flues 16 which open into the main draft flue 11 below the dampers 15 so that there is no interference with regulation by the dampers 15 of the main draft.

At intervals the opposite sides of the kiln are provided with outlets or ports 17 at points between the main draft outlets 14 and the furnaces 5. The size and number 15 of these outlets 17 may vary according to conditions. Each outlet is controlled by a damper 18 of any desired type, enabling the regulation of the draft to be carried on at any point or points desired.

20 There are draft outlets 19, of any desired number, leading from that portion of the kiln proper 4 which is located in advance of the main draft outlets 14 and between said outlets and the entry portion of the kiln, said outlets 19 leading to flues 20 which communicate with the down flues 12 below the dampers 15. Any suitable dampers 21 are provided for the outlets 19 so that any desired control thereof may be obtained.

30 The even graduation of heat in the tunnel through a wide range of temperatures is obtained, not alone by the use of the outlet 17 and dampers 18, but by drawing the heat beyond the main draft outlets 14, that is, into 35 the entry portion of the kiln where the ware is first subject to the heat after leaving the air lock 1. In consequence, heating of the ware begins immediately it enters the kiln and is graduated from that point on, the 40 regulation or graduation of the heat being accomplished by proper setting of the dampers 21, as well as the dampers 15 and 18.

Referring to Fig. 1, it will be seen that 45 the outlets 14 (and likewise outlets 17, 19) are located above the refractory platform 36 of the car which carries the ware 37 and that the edges of said platform travel in channels 38 in the walls of the tunnel. The 50 wheels 39 run on rails 40. The mechanical parts of the car or conveyer are, therefore, located in a space 41 below the platform 36, said space being filled with semi-inert air which acts as an insulator from the heat in 55 the upper portion 42 of the tunnel. The semi-inertness of the air in the space 41 is due to the fact that this space is sealed from the outside air and has no direct connection with any draft outlet, except by leakage 60 around the edges of the platform 36 where they loosely project into the channels 38.

In the floor 43 of the kiln there are provided openings 44 and 45 (Figs. 1 and 3) 65 which are controlled by dampers 46 and 47,

respectively. Usually one or two of these openings is sufficient, but their number may be increased according to the requirements under which the kiln is to be operated. Outside air may be supplied to the openings 70 in any preferred manner, a convenient plan being the provision of inspection tunnels 48, 49, Figs. 1, 2, 3. These tunnels 48, 49 may communicate with several kilns. By suitable adjustment of the dampers 46, 47, it is 75 possible to maintain a circulation of air from the space below the protecting platform 36 upwardly through the points of leakage from the space 41 to the space 42 at a rate which will not interfere with conditions to be maintained above the platform 36, but which will have sufficient cooling effect to prevent the accumulation of injurious heat in the space 41 below the platform. In that connection, it is to be noted 80 that however well the mechanical parts below the platform 36 may be insulated by the said platform and the semi-inert air space 41, it might be possible to accumulate injurious heat in the space 41 under extreme 85 conditions, if it were not possible to renew the supply of air either at intervals or continuously, at the proper rate.

By thus dividing the tunnel into upper and lower strata, comprising an upper section 90 in which the burning operations are conducted at high temperature, and a lower section containing the mechanical parts for carrying the ware, the temperature in the lower section being maintained at a suff- 95 ciently low point not to injure said mechanical carrying parts, a balanced condition exists between the upper and lower sections 100 which prevents downward draft from the higher to the lower temperature and renders 105 possible the admission from below of sufficient cool air to maintain the low temperature required in the lower section. This method of balancing of the draft renders unnecessary the provision of sand seals or 110 means to hermetically seal the upper section from the lower section.

While I have shown and described the invention in connection with a kiln such as set forth in my application Serial No. 175 152444 (of which this application is a division) to illustrate means for causing a draft in the kiln to maintain the air leakage from the semi-inert air space or section 41 upwardly past the edges of the car platform 120 36 into the upper space 42 of the tunnel, the present method and means for carrying it out are not limited to use in connection with the kiln of my application Ser. No. 152444 and can be applied to any kiln 125 having ware-conveying means.

Having thus described my invention, what I claim as new and desire to secure by Letters Patent, is:

1. In a kiln having ware-conveying means, 130

- draft balancing means adapted for maintaining an upper section in which the burning operations may be conducted at high temperature, and a lower section in which a lower temperature is maintained to prevent injury to the ware-conveying means, the said upper and lower sections being sealed from each other except for air leakage from the lower section into the upper section.
2. In a kiln, a conveyer having a ware-supporting deck or platform which substantially sub-divides the kiln into an upper section in which burning operations may be conducted at high temperature, and a lower section in which the temperature is maintained low enough to prevent injury to the conveyer, the said upper and lower sections being sealed from each other except for air leakage from the lower section into the upper section, and regulable means for admitting air to the lower section to control the air leakage and to maintain the relatively low temperature required therein.
3. In a kiln having ware-conveying means, draft balancing means adapted for maintaining an upper section in which the burning operations may be conducted at high temperature, and a lower section in which the temperature is maintained low enough to prevent injury to the ware-conveying means, the said upper and lower sections being sealed from each other except for air leakage from the lower section into the upper section, and controlling means for regulating the air leakage from the lower section into the upper section.
4. A kiln having an upper section in which the burning operations may be conducted at high temperature, a lower section containing semi-inert air, and means for controllably maintaining air leakage from the lower section into the upper section, said sections being otherwise sealed from each other.
5. A kiln having an upper section in which the burning operations may be conducted at high temperature, a lower section containing semi-inert air, means permitting air leakage from the lower section into the upper section, and regulable means for admitting cooling air into the lower, semi-inert air, section, said sections being otherwise sealed from each other.
6. A kiln having a conveyer provided with a ware-supporting deck or platform which substantially sub-divides the kiln into an upper section in which burning operations may be conducted at high temperature, and a lower section containing semi-inert air serving as an insulator to prevent injury to the ware-conveying means, the said upper and lower sections being sealed from each other except for air leakage from the lower section into the upper section, and regulable means for causing admission of cooling air to the lower, or semi-inert air, section to control the temperature therein.
7. The method of balancing the draft in a kiln employing ware-supporting means, consisting in causing a regulated flow of air leakage from the space below the ware-supporting means to the space in which the ware is located.
8. The method of balancing the draft in a continuous tunnel kiln employing ware-conveying means, consisting in causing a regulated flow of air leakage from the space below the ware-conveying means to the space in which the ware travels.
9. The method of balancing the draft in a continuous kiln having upper and lower sections, consisting in maintaining controllable air leakage from the lower section into the upper section thereof.
10. The method of balancing the draft in a continuous kiln having ware-supporting means, consisting in maintaining a predetermined air curtain between the ware-supporting means and the walls of the kiln by air leakage from the space below the ware-supporting means into the space in which the ware is located.

In testimony whereof, I hereunto affix my signature.

JOHN B. OWENS.
